(57) **CLAIM**

The ornamental design for a kiosk as shown and described.

DESCRIPTION

1. Kiosk
- 1.1 : Perspective
- 1.2 : Front
- 1.3 : Back
- 1.4 : Left
- 1.5 : Right
- 1.6 : Top
- 1.7 : Bottom

FIG. 1 is a perspective view of a kiosk; FIG. 2 is a front view thereof; FIG. 3 is a rear view thereof; FIG. 4 is a left side view thereof; FIG. 5 is a right side view thereof; FIG. 6 is a top view thereof; and FIG. 7 is a bottom view thereof. The broken lines in the figures depict portions of the kiosk which form no part of the claimed design.

1 Claim, 7 Drawing Sheets
